L. S. Bacon Le Roy, N.Y.

Letters Patent (Design No. 61) dated 28th July 1846

The Schedule referred to in these Letters Patent and making part of the same:

To all whom it may concern:

Be it known that I,

Lathrop S. Bacon of Le Roy in the County of Genesee & State of New York have invented or produced new shapes or configurations to Stove Plates which when combined with other plates make a cook stove and I do hereby declare that the following is a clear full & exact description of the same, reference being had to the accompanying drawings, making a part of this specification, in which Fig. 1, represents a perspective view of a cook stove after my plan. Fig. 2 represents a perspective view of the shapes of the back Bottom, the end or hearth part of which is seen at letter A. Fig. 1. Fig. 3 represents the shape & configuration of the jamb to the fire chamber and is not seen in Fig. 1 it being opposite to the door jamb as seen at letter B - Fig. 1. Fig. 4. represents a perspective view of the bottom of the oven - the oven being assisted in elevation by the vaselike shape given to it, and its location is seen at letters C. & C. Fig. 1. Fig. 5. represents a view of the shape or configuration of the front & back oven plate (they being exactly alike) the location of the front plate being seen at letter D. Fig. 1. Letter C. Fig. 1 represents the shape and configuration of the front of the fire chamber plate. Letter B. Fig. 1 represents the door jamb plate the first or largest door communicating with the main fire chamber, and the small one with a smaller fire chamber formed by the shape given to the Back Bottom as shown by Fig. 2.

Des. 601

What I claim as my invention and desire to secure by letters patent is the shape & configuration of the stove plates represented by Fig. 2, Fig. 3, Fig. 4 & Fig. 5 also the plate represented at letter E. Right in combination with other plates to make a cook stove with an elevated oven.

Dated May 25th, 1846.
